[57] CLAIM

The ornamental design for a combined top and bottom
bedsheet set, as shown and described.

DESCRIPTION

FIG. 1 is a front elevational view of the combined top and
bottom bedsheets set showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The cross-hatching represents fabric and is understood to
extend uniformly throughout the surfaces represented.
